(57) CLAIM

The ornamental design for a pocketed child safety chair with tie straps, as shown and described.

DESCRIPTION

FIG. 1 is a front view of a pocketed child safety chair with tie straps;

FIG. 2 is a rear view thereof;

FIG. 3 is a bottom view thereof;

FIG. 4 is a top view thereof;

FIG. 5 is a right-side view thereof, the left side being a mirror image; and,

FIG. 6 is a front, perspective-view of a pocketed child safety chair with tie straps as shown attached with a chair and holding a child.

The chair and child are shown in broken lines in FIG. 6 for illustrative purposes only and form no part of the claimed design.

The drawings include standard drafting symbol patterns for representing cloth or fabric.
